United States Patent Office.

AARON CARVER, OF LITTLE FALLS, NEW YORK.

Letters Patent No. 102,369, dated April 26, 1870.

IMPROVEMENT IN PUMPS.

The Schedule referred to in these Letters Patent and making part of the same.

To all whom it may concern:

Be it known that I, AARON CARVER, of Little Falls, in the county of Herkimer and State of New York, have invented certain Improvements in Double-acting Pumps; and I do hereby declare that the following is a full, clear, and exact description thereof, reference being had to the annexed drawings making part of this specification, in which—

Figure 1 is an elevation.

Figure 2 is a central vertical section.

Figures 3 to 9 are views, on an enlarged scale, of detached portions of the pump.

The same letters are used in all the figures in the designation of identical parts.

This invention relates to the valves of pumps; and it consists in a peculiar construction thereof, as will be more specifically set forth hereinafter.

To enable those skilled in the art to make and use my invention, I will proceed to describe its construction and operation.

In the annexed drawings—

A represents the outer pump, barrel, or cylinder, made of a suitable diameter, and of sufficient length to receive and encircle the inner cylinder, in which the piston works and the valves.

Its upper end has a horizontal flange, to which the head B is secured, a suitable packing being confined between such head and flange to make a water-tight joint.

Its lower end is closed by the head C, which may be screwed into it, as shown, or secured to it in any other suitable and convenient manner.

The under surface of the head B has an annular groove, b, into which the upper end of the cylinder D recedes on securing the several parts of the pump together.

From the upper surface of this head, and surrounding the central aperture through which the hollow piston-rod passes, extends a tubular projection, B', to which the discharge-pipe is connected, said pipe extending upward to the surface, and surrounding the connecting-rod by which the piston is operated.

The lower head C has a large central aperture surrounded by an annular vertical flange rising from its inner or upper surface, and forming a seat for the foot-valve H, which closes this aperture.

A ring, C', is screwed or otherwise secured to the upper end of this flange, having also an annular vertical flange near its periphery, the outer diameter of which is equal to the inner diameter of the piston-cylinder which is placed over it, resting upon the outer portion of the ring.

The vertical flange of the ring C' rises some distance

above the foot-valve H, and has in its upper end a cross-bar, C'', to stop at the proper point the upward movement of the valve when opened by the pressure of the water.

A series of smaller openings are made in the head C around the large central aperture, and these openings are closed by a series of valves, I, the movement of which, when opened by the upward pressure of the surrounding water, is controlled by the ring C', which extends horizontally over them.

D represents the inner or piston-cylinder, resting with its lower edge upon the ring C', fitting neatly over its flange, and extending upward to the upper end of the inclosing-cylinder A, recedes into the annular groove in the head B, and is thus held firmly in position. A series of openings, D', near its upper end, are the only means of communication between its interior and the surrounding cylinder A.

The piston E is a short tube with a peripheral recess to receive the packing necessary to make a tight joint between it and the cylinder D, in which it works. Its lower end is fitted with a disk, E', conveniently secured to it, and which has openings e' e' near its periphery, in form and size like the openings e e in its upper permanent disk, as clearly shown in fig. 5.

The hollow piston-rod F may be cast in one piece with the piston, rising centrally and vertically from its upper disk, as shown in the drawings; or, it may be constructed separately, and fastened to the piston. In either case, its aperture must communicate with the interior of the piston. The length of this hollow rod, or portion of the piston, as the case may be, is such that its openings F', through which the water is discharged into the discharge-pipe, are always above the hub on the head B, through which it works airtight. Its upper end is closed, as shown, and to it may be attached a connecting-rod passing upward to the surface, and operated in any convenient manner.

G represents the piston-valve, which alternately closes the openings in the upper and lower disks of such piston. It is a circular plate of metal, fitting loosely in the piston, and it has a central opening of the diameter of the chamber in the hollow piston-rod.

The valves H and I are alike in construction, and consist of a circular disk of sufficient diameter, provided with downwardly-projecting wings or guides, in the usual manner, between which disk and upper edge of the guides an elastic packing-ring, H', is interposed. The guides are not directly connected to the upper disk of the valve, but to a collar formed upon the under surface of such disk, which collar is made of a somewhat smaller diameter than that of a circle described over the outer surfaces of the guides, so that

the latter project beyond the periphery of the collar, as shown in the drawings.

The elastic packing-ring, which has an opening of suitable size to firmly embrace the collar, is introduced over the guides by spreading its opening, which, on coming opposite the collar, contracts around it, and is prevented from leaving its place by the projecting portions of the guides. The valve, thus made, is very cheap and effective, and is very easily repaired when worn, it being only necessary to provide it with a new packing-ring.

The operation of the pump may be described as follows:

All its parts having been constructed and arranged as above set forth, the pump may be placed in a well, partly or wholly immersed, and the piston put in motion. If the position of the piston at the beginning of the operation be that shown in fig. 2, the up-stroke creates a vacuum under it in the cylinder D, causing the water to lift the foot-valve H and fill the space. At the same time, the space above the piston being diminished, a corresponding quantity of air is discharged through the openings *e* in the upper disk of the piston and the hollow piston-rod. All this while the piston-valve G is held down upon the lower disk of the piston by its own gravity, and the foot-valves I remain closed for the same reason. At the moment the movement of the piston is reversed the foot-valve H is shut down and the piston-valve G forced against its upper seat, allowing the water in the cylinder D to enter the hollow piston-rod through the openings *e' e'* in the lower piston, disk, and aperture in the valve.

By this down-stroke a vacuum is formed above the piston in the cylinder D, and, as this communicates by means of openings *D'* with the surrounding cylinder A, consequently, in the latter, which causes the water to lift the foot-valve I and enter into such outer cylinder. The next up-stroke will close the foot-valves I, return the piston-valve to its lower seat, and again lift the foot-valve H to fill the space under the piston in the cylinder D with water. A portion of the water already in the piston-rod will enter the cylinder D, above the piston, during the first few strokes until all the air has been discharged from the pump. As soon as this is accomplished, the water will be forced up the hollow piston-rod continually. During the down-stroke the water under the piston in cylinder D is forced up through the openings *e' e'* in the lower disk of the piston, and the central aperture of the valve G. During the up-stroke the water above the piston is forced up through the openings *e e* in the upper disk of the piston.

Having thus described my invention,

What I claim, and desire to secure by Letters Patent, is—

The valve H, constructed with an annular groove between its disk and its guides, to receive and retain an elastic packing-ring, substantially as set forth.

In testimony whereof I have signed my name to this specification in the presence of two subscribing witnesses.
